UNITED STATES PATENT OFFICE.

JOSEPH PIERRE VOGEL, OF PITTSBURGH, PENNSYLVANIA, ASSIGNOR TO HEYL & PATERSON, INC., OF PITTSBURGH, PENNSYLVANIA, A CORPORATION OF PENNSYLVANIA.

MATERIAL-HANDLING APPARATUS.

Application filed July 25, 1921. Serial No. 487,316.

To all whom it may concern:

Be it known that I, JOSEPH PIERRE VOGEL, a resident of Pittsburgh, Allegheny County, Pennsylvania, have invented a new and useful Improvement in Material-Handling Apparatus, of which the following is a full, clear, and exact description.

My invention relates broadly to material handling apparatus, and more particularly to mining machinery for handling materials of different kinds or different grades of the same kind of material. My invention is especially applicable to the handling of coal and rock in such manner as to keep the same separated after they are dumped from the ordinary mine cars, bringing the material from the face of the mine.

An object of the invention is the provision of apparatus of capacity to simultaneously receive material from separate carriers and deliver the material from each carrier to the same or different points.

Another object of my invention is to provide an apparatus which is efficient in operation and which will accomplish the desired purpose, without the necessity of uncoupling or switching the cars containing the different material or materials of different grades.

Further objects and advantages of my invention will be apparent upon reference to the following description taken in connection with the accompanying drawings illustrating one application of my invention and in which:

Figure 1 is a plan view of a device embodying my invention;

Figure 2 is a side elevation of a device embodying my invention looking in the direction of the arrows II—II of Figure 3;

Figure 3 is an elevation of a device embodying my invention looking in the direction of the arrows III—III of Figure 2.

In the handling of material, such as coal and rock, taken from a mine, the coal is loaded in cars by hand and the rock is loaded in other cars by hand, and the cars containing coal and rock are coupled together and carried by some suitable power device to a desired point. My invention is particularly concerned with the problem of removing these materials from the mine to the surface while keeping them separated.

It has been proposed heretofore to un-

couple and switch the cars containing the different materials, and group the cars containing like material before carrying the same to the surface and dumping the same. This method requires space and trackage for switching the rock cars from the coal cars, and some kind of means for hoisting each to the surface, or at least, some separate means for carrying the coal and rock to the surface. This extra trackage and space are expensive and difficult to obtain when these operations are carried on underground as they customarily are.

It has been proposed also to assemble the cars and haul them to the surface by some kind of conveyor, or to sink a vertical shaft and provide a skip hoist for the purpose of carrying the cars with the rock or coal to the surface and dumping the same. This method usually makes it necessary to provide the cars with loose ends which involve a considerably higher maintenance than the solid type which I am enabled to use by my invention.

By my invention, the string of cars containing rock at regular or irregular intervals is carried to a suitable point and the cars are dumped without uncoupling and without regard to their contents; and means are provided for directing the contents of like character to one point and the contents of like character of different kind from the first to another point, means being provided to direct material from the dumping station to either of the points desired.

By reference to the drawings, a string of cars illustrated in dotted lines in Figure 2 is brought up on the tracks 1. A trip feeder 2 takes the cars and moves them into the rotary dump 3, which has tracks registering with the tracks 1. The rotary dump shown in the drawings is long enough to accommodate two cars as illustrated. The dump and the tracks, together with the cars, are so proportioned that the axis around which the dump rotates passes through the center of the coupling 4 of the cars. The dump may be of any desired detail construction, but is usually provided with a gear 5, extending therearound and co-operating with the pinion 6, which is operated by a motor 7. The dump is suitably supported at its center and ends so as to carry the load

of the cars when they pass into the dump. Car spotters 8 and 9 are placed on the track so as to insure the proper position of the cars in the dump. Below the dump is a compartment or receiving hopper 10. This hopper constitutes two compartments 11 and 12 respectively. The compartments of the hopper correspond in position to the position of the cars in the dump 3, during the dumping operation, so that the contents from the car 13 will fall into the compartment 11 and the contents of the car 14 will drop into the compartment 12. Each of the compartments 11 and 12 is provided with a fly gate 15, hinged at 16, and operated by a pneumatic piston and cylinder or other suitable means 17. Each fly gate controls two outlets from its respective compartment. One of said outlets 18 from each compartment leads to a weigh box 19 for coal, and the other outlet from each compartment delivers to a common chute 20 for conducting the rock to any desired point. From the chute 20, the rock is carried into a storage hopper 21, having a pneumatically controlled gate 22, across the lower end thereof. A skip 23 co-operates with the lower end of the storage hopper 21, so that, upon the operation of the gate 22, the rock will discharge into the skip or other suitable device, and be conducted from there to any desired point, usually to the surface.

The coal passing from each compartment 11 or 12 through its outlet 18 into the corresponding weigh box is weighed, and is then discharged into a chute 24, delivering to an apron feeder 25. From either apron feeder, the coal is conducted onto a corresponding bar screen 26, which allows the finer pieces of coal to pass through onto a corresponding inspection table 27. The arrangement at this point is such that the fine coal falls onto the inspection table, which usually consists of a belt, and thus forms a layer of soft material on the belt, upon which the larger particles of coal fall from the end of the bar screen 26. This has a double advantage, in that the layer of fine coal protects the belt from mutilation by large pieces of coal, and furthermore, this layer forms a cushion for the large pieces of coal to fall upon which prevents breakage of the coal to a considerable extent. Furthermore, this arrangement causes the larger pieces of coal to be on top of the inspection table, so that the inspector may more readily inspect the different pieces than if the two were intermixed. The coal is conducted by each inspection table through a chute 28 onto a common belt conveyor 29, leading to the surface. All of the various moving parts, such as the inspection tables, apron feeders, etc., may be operated by suitable motors and gears, or otherwise. These operating means are so well known that a detail description

thereof would merely encumber this specification, without aiding in an understanding of the invention.

The outlet from each weigh box is operated through a counterweighted cord 30 by an operator who is stationed in a compartment, with the indicating element of the scale 31.

The operation of my invention is as follows: The cars are filled at the face of the mine, some with coal and some with rock. The train of cars is brought in any desired manner to the trip feeder 2. This trip feeder is operated by any suitable power device and is arranged to move the cars to the right, as shown in Figure 2. When the first car of the train is brought under the control of the trip feeder, the engine or other motor for hauling the train may be disconnected. The trip feeder moves the train so that the first two cars are in the rotary dump 3. This is determined by the position of the third car with relation to the spotter 8. The train is then stopped and the motor 7 started which, through the gears 5 and 6, rotates the dump 3, together with the two cars therein. Assuming that the first car of the train in the dump contains rock and the second car coal, the fly gate of compartment 12 would have the position shown in full lines in Figure 3, and the fly gate for the compartment 11 would have the position shown in dotted lines in Figure 3. When the dump 3 rotates sufficiently, the contents of the cars will be dumped, the rock falling into the compartment 11 and the coal into the compartment 12. The coal will go immediately into the corresponding weigh box 19 and as soon as it is weighed will be discharged into the corresponding chute 24, and from there on to the corresponding apron feeder 25 and inspection table, and from there onto the common belt conveyor 29, leading to the surface or other desired point.

The rock will be discharged from the compartment 11 into the chute 20, delivering into the storage hopper 21, and when a sufficient amount of the rock has been discharged into the storage hopper 21, the gate 22 is raised and the rock skip 23, or other suitable device, is loaded and is then conducted to the surface or other desired point and the rock discharged.

After the first two cars of the train have been dumped, the dump 3 is rotated again to its normal position and the trip feeder is operated to bring the next two cars in position, whereupon the operation above explained is repeated. In this case, however, the rock may be in the fourth car and the coal in the third car of the train, in which event, the fly gates would be reversed in position and the same ultimate result obtained. The next two cars, that

is 5 and 6, may both contain coal, in which case, the fly gates would be so positioned as to conduct the coal from both compartments 11 and 12 into both weigh boxes. 5 On the other hand, these two cars may both contain rock in which event, the fly gates would be so positioned that both the compartments 11 and 12 would discharge into the storage hopper 21, through the chute 10 20.

It will be seen that the present invention provides an apparatus for accommodating, either simultaneously or successively, carriers, certain of which may contain one kind 15 of material and certain others of which may contain a different kind of material, as, for instance, coal and rock, and for receiving the contents of such carriers and distributing the same to suitable delivery points, 20 while maintaining the different kinds of materials separated. While the apparatus is intended for normally handling a plurality of kinds of material, either simultaneously or substantially simultaneously, 25 it is also adapted for the handling of one kind of material only for a given period of time, and for the subsequent handling of a different kind of material for another given period of time.

30 It will be apparent that many changes may be made in the details of the various elements constituting my invention, without departing from the spirit thereof. I am therefore not to be limited to the particular means illustrated, but my invention is broad enough to include any particular elements co-operating to effect the functions illustrated in the embodiment shown and covered by the annexed claims.

40 I claim:

1. In apparatus of the character described the combination of a dumping station for simultaneously accommodating a plurality of material carriers to be dumped, individual means for receiving the material from each of said carriers, and means associated with each of said receiving means whereby to direct all of the material received thereby at will to any of a plurality of delivery points each of which is common to all of such receiving means, substantially as described.

50 2. In apparatus of the character described, the combination of a dumping station for simultaneously accommodating a plurality of material carriers to be dumped, individual means for receiving the material from each of said carriers, means for direct-

ing all of the material from each of said receiving means to any of a plurality of 60 delivery points each of which is common to all of such receiving means, and individual means for receiving and handling the material delivered in any of said directions, 65 substantially as described.

3. In apparatus of the character described, the combination of a dumping station for simultaneously accommodating a plurality of material carriers to be dumped, an individual compartment for receiving the material from each carrier, delivery means leading from each of said compartments to a common delivery point, delivery means leading from each of said compartments to a second common delivery point, and means 70 associated with each of said compartments for directing the material received thereby to either of the delivery means leading therefrom, substantially as described.

4. In apparatus of the character described, the combination of a dumping station for simultaneously accommodating a plurality of material carriers to be dumped, individual means for receiving the contents of each of said carriers, means for directing at will all of the material received by each of said receiving means to any of a plurality of delivery points each of which is common to all of such receiving means, and means for weighing the material delivered in one direction from each of said receiving means, substantially as described.

5. In apparatus of the character described, the combination of a dumping station for simultaneously accommodating a plurality of cars to be dumped, certain of said cars containing coal and certain others rock, an individual compartment for receiving the contents of each car and having provision for directing the rock in one direction and the coal in another direction at will, a conveyor for removing the rock, means for conducting the rock from the compartments containing the same to said conveyor, means for weighing the coal received by each compartment, inspection means for receiving the coal from each of said weighing means, and a conveyor for receiving the coal from all of said weighing means and conducting the same to a suitable delivery point, substantially as described.

100 In testimony whereof, I have hereunto set my hand.

J. PIERRE VOGEL.
